CLAIM

The ornamental design for a gas detector, as shown and described.

DESCRIPTION

FIG. 1 is a left, front perspective view of a gas detector showing my new design;

FIG. 2 is a front elevational view of the gas detector of FIG. 1;

FIG. 3 is a left side elevational view of the gas detector of FIGS. 1 and 2;

FIG. 4 is a right side elevational view of the gas detector of FIGS. 1-3;

FIG. 5 is a rear elevational view of the gas detector of FIGS. 1-4;

FIG. 6 is a top plan view of the gas detector of FIGS. 1-5; and,

FIG. 7 is a bottom plan view of the gas detector of FIGS. 1-7.

The broken line showing of structural features is included for the purpose of illustrating non-claimed subject matter and forms no part of the claimed design.
